Des. 202,857
Patented Nov. 9, 1965

202,857

COMBINED CIGARETTE SNUFFER AND DESK ORNAMENT

Franklin N. Jacek, 37 Madison Ave., New York, N.Y.

Filed Nov. 5, 1964, Ser. No. 82,479

Term of patent 14 years

(Cl. D85—2)

Fig. 1

Fig. 2

Fig. 3

Fig. 4

I claim:

The ornamental design for a combined cigarette snuffer and desk ornament, as shown.
